DESIGN FOR A VENDING MACHINE CABINET

James E. Stewart, Rye, N. Y.

Application January 14, 1941, Serial No. 98,031

Term of patent 3½ years

To all whom it may concern:

Be it known that James E. Stewart, a citizen of the United States and resident of the city of Rye, in the county of Westchester and State of New York, has invented a new, original, and ornamental Design for a Vending Machine Cabinet, of which the following is a specification, reference being had to the accompanying drawing forming part thereof, in which Figure 1 is a front

elevation of the vending machine cabinet, showing my new design; Figure 2 is an elevation as seen from the right side; and Figure 3 is a plan view of the cabinet as viewed from above.

I claim:

The ornamental design for a vending machine cabinet, as shown.

JAMES E. STEWART.
